UNITED STATES PATENT OFFICE.

ALBERT D. GROVER, OF NEW YORK, N. Y., ASSIGNOR, BY MESNE ASSIGNMENTS, TO AUTOSALES CORPORATION, A CORPORATION OF NEW YORK.

COIN-CONTROLLED VENDING MACHINE.

1,418,301.

Specification of Letters Patent. Patented June 6, 1922.

Original application filed April 8, 1916, Serial No. 89,752. Divided and this application filed May 4, 1917. Serial No. 166,296.

To all whom it may concern:

Be it known that I, ALBERT D. GROVER, a citizen of the United States, and a resident of New York city, in the county of New York and State of New York, have invented certain new and useful Improvements in Coin - Controlled Vending Machines, of which the following is a specification.

My invention relates to coin-controlled vending machines and has for its object the provision of a machine of small dimensions and large capacity.

Vending machines which are adapted for use in theatres and other places where but little space is available, must be of small dimensions, particularly as to depth, so as not to constitute an obstruction. At the same time the machine should have a sufficiently large capacity to obviate frequent filling. This is especially desirable in the case of machines installed for operation in moving picture theatres or the so-called continuous vaudeville houses where no opportunity is afforded for replenishing the machines after the beginning of the performance until after the close.

The machine of my invention fulfils the above and other requirements, in that it is of small outside dimensions, has a coin-controlled mechanism which is exceedingly simple in construction and efficient in operation, and is provided with a goods-magazine which occupies almost the full height of the casing and thereby provides the machine with a maximum capacity.

The various objects and advantages of my invention will become apparent from a detailed description of the accompanying drawings which form part of this specification and which show an embodiment of my invention in the form in which it is now best known to me.

In the drawings—

Fig. 1 is a front view of a machine embodying my invention, the cover plate for the coin mechanism being omitted and a portion of the front wall of the casing being broken away for the sake of clearness to show certain parts within the casing.

Fig. 2 is a side view of Fig. 1, looking from right to left, a portion of the side wall of the casing being broken away to show the gate which normally closes the delivery opening.

Fig. 3 is a top plan view of Fig. 1. 55

Fig. 4 is a rear view of the machine with the rear wall of the casing broken away to show the working parts within, the parts being shown in normal position.

Fig. 5 is a vertical cross-section approximately on line 5—5 of Fig. 4, looking in the direction of the arrows. 60

Fig. 6 is a transverse cross-section approximately on the broken line 6—6 of Fig. 4, looking downwardly. 65

Fig. 7 is a fragmentary detail view showing how the coin is locked against return movement after being carried into the machine a predetermined amount.

Fig. 8 is a view similar to Fig. 4 with the parts shown in full operated position to eject a piece of goods.

Fig. 9 is a longitudinal section approximately on the broken line 9—9 of Fig. 8, looking in the direction of the arrows. 75

Fig. 10 is a top plan view approximately on the broken line 10—10 of Fig. 8, looking downwardly.

Fig. 11 is a fragmentary detail view showing the ejector and gate in normal position. 80

Fig. 12 is a view similar to Fig. 11, showing a piece of goods partly ejected from the magazine with the gate just opened to allow the goods to pass through.

Fig. 13 is a view similar to Figs. 11 and 12, with the piece of goods fully ejected, the ejecting lever having partly returned to normal position. 85

Fig. 14 is a fragmentary detail view showing how the segment which supports the goods during the ejecting operation is tripped by the bottom piece of goods, as the ejecting operation begins, into a position to slide readily beneath the second piece of goods; and 95

Fig. 15 shows how the ejecting lever is locked against return movement when the magazine is empty.

The closed outer casing of the machine is preferably made in two separable sections, 100 which for the sake of distinction I will designate as a flat section and a box-like section. The flat or rear section comprises a rear wall 1 having side flanges 2, a top 3 and a bottom flange 4. The front or box-like section 105 comprises a front wall 5 provided with a bottom 6 and sides 7 and 8. The two sections of the casing are formed of suitable

metal and when assembled they fit against each other to constitute a closed casing. The sides 7 and 8 of the front or box-like section fit against the side flanges 2 and top 3 of the 5 rear or flat section, and the bottom 6 of the box-like section fits over the lower flange of the flat section. Suitable locking means is provided for holding the sections in locked relation. The construction of the outer casing may, of course, be varied and I mention the foregoing construction merely by way of 10 illustration.

Within the casing is supported an upright goods-magazine designated as a whole by M. 15 This magazine is preferably formed of sheet metal and comprises a main wall 9, side walls 10 and longitudinal flanges 11 which serve to retain the pieces of goods in the magazine. The magazine is rigidly held in 20 place by any suitable means. In the present illustration the magazine is supported by the stud 12 near the bottom and by a pair of studs 13 near the top. The stud 12 also performs another function, as will appear 25 later on.

The bottom of the magazine is formed by a plate member 14 which is secured to the frame of the magazine by means of the upwardly turned rear flange 15 and the side 30 piece 16. The flange 15 is fastened to the side wall 10 of the magazine and the side piece 16 is fastened to one of the flanges 11. The bottom plate 14 of the magazine is provided with a laterally and upwardly extending 35 portion 17 which guides the ejected package from the discharge opening 18 at the bottom of the magazine to the delivery opening 19 formed in the side wall 7 of the casing. It will be observed that the discharge opening 18 of the magazine is below 40 the delivery opening 19. The advantage of this construction will be explained later on.

On the side wall 7 is slidably mounted a gate 20 which is held in place by studs 21 45 extending from the side wall of the casing. The studs 21 extend through slots 22 in the gate. This pin- and slot-connection also limits the up and down movement of the gate. In its normal position, as shown in 50 Figs. 1, 2, 4 and 11, the gate 20 fully covers the delivery opening 19. The position of the gate 20 is directly under the control of the ejecting lever 23 which is pivoted on the stud 24 secured to the front wall 5 of the casing. The lever 23 is provided with 55 a lateral arm or extension 25 to the outer end of which is secured the lower end of a contractile spring 26, the upper end of which is secured to the pin or stud 27 projecting 60 from the side wall 8 of the casing. The spring 26 holds the ejecting lever 23 normally in the position shown in Fig. 4 and returns it to that position after each operation of the machine. Of course, any suitable 65 spring means can be employed to main-

tain the ejecting mechanism in normal position and automatically restore it to that position after each ejecting operation. It will be observed from Figs. 5 and 9 that the lever 23 is mounted and operates within the 70 shallow space or chamber formed between the magazine and the front wall 5 of the casing. I might here explain that when I refer to the wall or plate 5 of the casing as the front wall or plate, I use the word 75 "front" merely in a relative sense, and I so want the word understood when used in certain of the appended claims. In the broader aspect of my invention, so far as the delivery mechanism is concerned, it is 80 immaterial whether the wall or plate which carries that mechanism constitutes the front or the rear of the casing when secured for operation to a suitable support, such as the back of a theatre chair. 85

At its lower end the lever 23 is provided with a laterally and rearwardly extending pin 28 which projects into the magazine through the rear slot 29 and lateral slot 30 thereof to push the bottom piece of goods 90 through the discharge opening 18 and the delivery opening 19 when the lever 23 is operated. The position of the ejected package is shown at P in Figs. 8 and 13.

The lever 23 controls and operates the 95 gate 20 through the arm 31 pivoted at 12 on the front plate 5. The arm 31 is at one end provided with a rearward extension 32 arranged to engage between the spaced lugs 33 of the gate 20. The other end of the 100 arm 31 is formed with an irregularly shaped cam-slot consisting of the portions 34, 35 and 36. From the lever 23 extends a pin 37 which engages in the cam-slot of the arm 31. During the normal position of the 105 parts, as shown in Figs. 4 and 11, the pin 37 of the lever 23 rests at the extreme outer end of the cam-slot—that is to say, in the portion 34. As the slot portion 34 is substantially in an arc struck up from the pivot 110 point 24 of the lever 23, the engagement of the pin 37 in the slot portion 34 positively locks the gate 20 in closing position. During the initial movement of the lever 23 toward the left (as viewed in Figs. 4 and 11), there is no corresponding movement of the gate 20, but as soon as the pin 37 enters the raising slot portion 35, the arm 31 is turned clockwise (as viewed in Figs. 4, 8 and 11), and the gate 20 is raised to fully 115 uncover the delivery opening 19. This open position of the gate, with the corresponding position of the pin 37 in the cam-slot, is shown in Fig. 12. The operation of the gate 20 is so timed with respect to the movement of the ejecting lever 23, that the gate is fully opened just as the bottom piece of goods is about to be projected through the delivery opening 19, as Fig. 12 clearly shows. Continued operation of the ejecting lever 23 120

from the position shown in Fig. 12, will push the bottom package P through the delivery opening 19 until it reaches the position shown in Figs. 8 and 13. The position 5 of the lever 23 at the end of its ejecting movement is shown in Fig. 8. During the time that the pin 37 passes through the slot portion 36, there is no movement of the arm 31, because the slot portion 36, when the 10 arm 31 is in the position shown in Fig. 12, forms approximately an arc struck up from the pivot point 24 of the lever 23 as a center. The slot portion 36 is, therefore, a rest or dwell portion and serves to hold the gate 20 15 in open position during the final forward movement of the ejecting lever as well as during the initial return movement thereof. Fig. 13 shows the lever 23 partially returned to normal position and about to close 20 the gate 20. The gate will, of course, not close until the ejected piece of goods P has been withdrawn from the machine. As soon as the gate 20 is thus released, the spring 26 25 draws the lever 23 and the connected parts back to normal position.

One of the important features of my invention is the means which I have provided for holding the second piece of goods (and, of course, the rest of the stack or column) 30 above the discharge opening 18 of the magazine during the time that the gate 20 is open. In this way it is impossible to obtain two pieces of goods from one operation of the machine. In the preferred form of my 35 invention, this supporting means is in the form of a segment 38 mounted on the ejecting pin 28. The normal position of the segment 38 is that shown in Fig. 11. When the ejecting operation begins, the rear edge of 40 the bottom piece of goods trips the segment into the position shown in Fig. 14. A further movement of the lever 23 causes the forward edge 39 of the segment to enter the slot 40 formed in the bottom plate 14 45 and engage the downwardly bent tongue 41 over which the segment 38 rides and is gradually and easily lifted into engagement with the second piece of goods P², as best shown in Fig. 12. In this way, the second 50 piece of goods, and all those above it, are supported out of alignment with the discharge opening of the magazine during the ejecting operation of the lever 23. It is, therefore, absolutely impossible to withdraw 55 the second piece of goods, even should the gate 20 be held open by some instrument after the previously ejected piece had been withdrawn. If we imagined the ejected piece P withdrawn, as shown in Fig. 13, and 60 the gate 20 held open by a knife blade or other instrument, the second piece P² would drop into the dotted-line position P', indicated in Fig. 12. It will be clear from that 65 figure that the package P' is firmly wedged or locked against withdrawal by the exten-

sion 17 of the bottom plate 14, the supporting segment 38 and the upper edge of the discharge opening 18 of the magazine. It will thus be seen that the supporting segment 38 positively prevents the withdrawal 70 of more than one piece of goods at each operation of the machine. When the lever 23 begins its return movement, as indicated by the arrow a in Fig. 13, the segment 38 rolls under the goods in the direction indicated by 75 the arrow b in Fig. 13. In thus rolling, the segment 38 causes no frictional retarding of the lever 23 and adds to the smooth and easy operation of the parts. When the lever 23 reaches the end of its return movement, 80 the segment 38 falls back into its normal position, as shown in Figs. 4 and 11, ready to repeat the movements above described at the next operation of the machine.

The movements of the supporting segment 85 38 and gate 20 are so timed relatively to each other that the segment is in supporting position as long as the gate is open. In other words, the goods are always elevated against attempted withdrawal while the delivery 90 opening 19 is left open by the gate. It will be seen from Fig. 13 that after the ejected package P has been withdrawn and the lever 23 allowed to return, as soon as the pin 37 enters the inclined slot portion 35 of the 95 arm 31, the gate 20 begins to descend. The segment 38 remains in supporting position until the pin 37 leaves the slot portion 35 and enters the slot portion 34, but by that time the opening 19 has been closed by the 100 gate 20.

I have provided means to lock the ejecting lever 23 against full return movement when the supply of goods in the magazine is exhausted. On top of the stack of goods rests 105 a weight or follower W which has a recess 42 on its underside. After the last package has been ejected and the parts return to normal position, the segment 38 engages in the slot 42 of the weight W and thereby locks 110 the lever 23 with its connected parts against further movement. This locked position of the parts is shown in Fig. 15.

If desired, a spring gate 43 may be pivoted at the bottom of the magazine to close 115 the discharge opening 18, as an additional safe-guard for the goods. While the goods cannot be removed from the machine except by operation of the ejecting mechanism, quite irrespective of the gate 43, the use of 120 this additional gate prevents the insertion of a sharp pointed instrument to mutilate the goods. However, the use of the gate 43 is by no means necessary, and I mention it merely as a matter of preference.

I will now describe the coin mechanism by means of which the ejecting lever 23 is actuated into ejecting position upon the deposit of a proper coin. To the front plate 5 of the casing is secured a casting or frame- 130

piece designated as a whole by F. This frame-piece is held in place by suitable fastening devices, such as screws or bolts 44, which enter the frame-piece from the inside of the casing, so as to prevent possible removal from the outside. The fastening members 44 enter the openings 44' of the frame-piece F, as shown in Fig. 1. The supporting frame-piece F is shallow and so 10 does not project much beyond the front plate 5 of the casing, as clearly shown in the drawings. On its inner side the frame-piece F is formed with a recess or chamber which forms the coin-passage 45 and in 15 which the rotatable coin-carrier 46 is operatively mounted. This coin-carrier comprises a disc having opposite notches 47 which receive the deposited coin and carry it through the coin-passage into engagement 20 with the pin 48 projecting forwardly from the upper end of the lever 23. The front plate or wall 5 of the casing is provided with an arcuate slot 49 through which the pin 48 projects, as best shown in Fig. 5. 25 The coin-carrier 46 is secured to the inner end of the stud 50 which projects through the frame-piece F and carries at its outer end a suitable form of finger piece 51.

In a recessed portion 52 formed in the 30 inner wall of the frame-piece F is movably mounted a latch member 53 provided with a lateral portion 54 which extends into the coin-chute 45 and is, therefore, in the path of the moving coin. The extension 54 has 35 a beveled edge 55 which the descending coin engages to move the latch member 53 out of obstructing position. After the coin has been carried downwardly in the coin-carrier past the beveled edge 55 of the latch member 40 53, the coin becomes locked against return movement by the straight edge 56 of the extension 54 engaging the edge of the coin. Fig. 7 shows the coin in a position in which it has just been locked against return movement by the member 53. In other words, 45 after the coin has been carried into the machine a predetermined distance, the coin-carrier cannot be rotated reversely, but the forward movement must be completed. 50 This locking of the coin and coin-carrier against reverse movement occurs before the gate 20 is fully opened in the operation previously described. The latch member 53 is returned to normal position by a spring 57 55 mounted in the slot or recess 58 of the latch member. The lower end of this spring bears against a fixed lug 59 projecting rearwardly from the front wall 5 of the casing, while the upper end bears against the top of the 60 slot or recess 58.

The operation of the coin-mechanism as so far described will now be clearly understood and may be briefly summarized as follows: When a coin is inserted into the 65 coin-entrant slot 60, it falls on to the edge

of the coin-carrier 46. If neither of the coin-receiving notches 47 happens to be in proper position, the coin will rest on the peripheral edge of the coin-disc 46. When the finger piece 51 is then rotated clockwise 70 (as viewed in Fig. 1—or counter-clockwise, as viewed from the rear of the machine, as shown in Figs. 4 and 8), the coin will drop into one of the notches 47 and will be carried by the disc 46 through the coin-passage 75 45. The upper wall 61 of the coin-passage is so curved as to retain the deposited coin C in the carrier. As the coin descends, it rides over the inclined edge 55 of latch member 53 and thereby pushes the latter out 80 of the way. As rotation of the coin-carrier continues, the coin is brought against the pin 48 of the ejecting lever 23, whereupon the latter is rocked to eject the bottom piece of goods, as previously described in detail. 85 The position of the coin when the lever has been moved into full operative position is indicated at C in Fig. 8. Continued rotation of the coin-carrier raises the coin over the pin 48 and allows it to drop into the 90 passage way 62 whence it slides over the inclined portion 63 of the frame-piece F into the shallow chamber between the front wall of the casing and the magazine M. A suitable coin-box 64 may be placed at the bottom 95 of the casing to receive the discharged coins.

On the stud 65 projecting from the front plate 5 of the casing is pivoted the gravity latch 66 which carries at its upper end a pin 67 projecting forwardly through the slot 68 100 in the plate 5 into the path of movement of the extension 54 of the latch slide 53. The latch 66 has a weighted portion 69 which normally holds the pin 67 in position to engage the lower edge 70 of the extension 54 105 of the slide 53, as shown in Fig. 8. The gravity latch 66 is provided with an arm 71 which is engaged by the ejecting lever 23, when the latter is in normal position as shown in Fig. 4. When the gravity latch 110 66 is so held by the lever 23, the pin 67 is out of alignment with the latch slide 53, as shown in Fig. 4. However, as soon as the lever 23 moves out of normal position, the gravity latch 66 swings into its normal or locking position to prevent complete downward movement of the latch slide or member 53. Therefore, should a coin be deposited when the supply of goods is exhausted, the coin-carrier will be stopped 115 against rotation as soon as the coin has pressed the latch member 53 downwardly into engagement with the pin 67 of the gravity latch 66. This occurs before the coin has reached the locking position shown 120 in Fig. 7, so that reverse rotation of the coin-carrier is permitted to carry the coin back through the coin-entrance slot 60 for removal by the intending purchaser. In 125 this way the loss of the deposited coin is 130

prevented when there are no goods in the machine.

The lever 23 is at its upper end provided with a curved extension 72 which has teeth 73 adapted to receive the double-acting pawl 74 pivoted on the stud 75 projecting rearwardly from the front plate 5. The pawl 74 is held in normal position by a suitable spring 76 supported from the pin or stud 77 carried by the front plate 5. The two-way pawl 74 by engaging the teeth 73 prevents the return of the lever 23 until the package of goods has been fully ejected.

I have also shown coin-testing mechanism associated with the coin-carrier to prevent operation of the lever 23 with magnetic discs and washers. This coin-testing mechanism is mounted in the recess or chamber 78 formed in the front wall of the supporting frame-piece F. A plate f covers the recess or chamber 78. The magnetic coin tester comprises a permanent magnet 79 mounted to swing on the pin or stud 80 carried by the frame-piece F. The poles 81 of the magnet are bent to extend through an opening 82 in the frame-piece F approximately flush with the front wall of the coin-passage 45, as best shown in Fig. 6. At its lower end the magnet, or the frame on which it is mounted, carries a stop 83 which is normally out of alignment with the slot or recess 84 in the latch member 53, as shown in Figs. 4 and 8. When a magnetic disc is deposited and carried past the poles of the magnet, the magnetic attraction will swing the magnet toward the left (as viewed in Figs. 4 and 8), and thereby bring the stop 83 into alignment with the slot 84 of the latch member 53. Continued movement of the magnetic disc in the coin-carrier will deflect the latch member 53 downwardly until arrested by the stop 83 engaging in the slot 84. This positively locks the magnetic disc and coin-carrier against further movement. However, the coin-carrier may be rotated in the reverse direction to carry the magnetic disc back through the coin-entrance slot whence it may be removed.

To prevent the operation of the machine when a non-magnetic washer is deposited, I provide a pawl 85 pivotally mounted at its lower end in the lug 86 which is arranged in the chamber 78 of the frame-piece F, as best shown in Fig. 1. At its outer end the pawl 85 extends through an opening in the frame-piece into the coin-passage 45 so as to be in the path of the moving coin. A suitable spring 87 mounted on the stud 88 of the frame-piece F presses the pawl 85 and yieldingly holds it in the path of the coin. When a good coin is in the coin-carrier the pawl 85 is repressed and allows the coin to pass. However, when a ring or washer is in the coin-carrier, the upper end of the pawl 85 snaps into the opening of the ring or washer

and thereby locks the same against further entrance into the machine. The head of the pawl is beveled on the underside so that the locked ring or washer may be withdrawn by rotating the carrier in the reverse direction.

The above described magnetic coin-tester and washer-catcher form no part of my present invention, but are the joint invention of Earl E. Barber and myself, and form the subject-matter of the co-pending Grover and Barber application, Serial No. 762,810, filed April 22, 1913, and the divisional application, Serial No. 58,544, filed October 29, 1915.

Although I have herein described and shown a machine of specific construction, I would have it distinctly understood that I do not intend to be limited to the details of construction herein set forth, as it is obvious that the various features of novelty which characterize my invention may be mechanically carried out in other ways than that set forth by way of illustration.

I will add that this application is a division of my pending application Serial No. 89,752 filed April 8, 1916. Owing to an official requirement for division, the claims in said original application have been restricted to the delivery features of the invention, while the claims in this additional application are directed to the coin-controlled features.

Having thus described my invention, what I claim as new and desire to secure by Letters Patent of the United States, is:

1. In a coin-controlled vending machine, a movable coin-carrier, an ejecting member adapted to be operated by the coin in said coin-carrier, locking means adapted to be moved aside by the coin in said coin-carrier, and a latch held normally in an inoperative position by said ejecting member, said latch being automatically released when said ejecting member is out of normal position to lock said means in locking position and thereby lock the coin in the coin-carrier against operative movement in the machine, said coin-carrier being movable in the reverse direction to permit withdrawal of the coin.

2. In a coin-controlled vending machine, a magazine for the vendible goods, a device for ejecting the goods from said magazine, a rotatable coin carrier for conveying the deposited coin into engagement with said device to operate the same, a yieldable obstruction in the path of the coin on the carrier, and means whereby said obstruction is automatically locked against yielding when the magazine is empty, so that the coin is locked by said obstruction against operative movement in the machine, said coin-carrier being movable in a reverse direction to lift the coin out of the coin-entrance slot for withdrawal.

3. In a coin-controlled vending machine, a casing provided with a delivery opening, a gate for normally closing said delivery open-

ing, a magazine for the vendible packages, mechanism for ejecting the packages from said magazine, said gate being mounted independently of said mechanism, means whereby said mechanism automatically opens said gate during the ejecting operation, a hand-operable rotatable coin-carrier for actuating said mechanism through the medium of the deposited coin, and means whereby 10 the coin-carrier is locked against reverse rotation before said gate is opened.

4. In a coin-controlled vending machine, a casing provided with a coin-entrance slot, a movable coin-carrier for conveying the coin 15 into operative position, an operating member arranged to be engaged and actuated by the coin in the carrier, a yieldable element in the path of movement of the coin and adapted to be moved out of the way by the coin, 20 and a normally inoperative device for automatically locking said element against movement when said member is out of normal position, whereby the coin in the coin-carrier is locked against operative movement in the 25 machine, said coin-carrier being movable in the reverse direction to permit withdrawal of the locked coin through the coin-entrance slot.

5. In a coin-controlled vending machine, 30 a casing provided with a coin-entrance slot, a magazine for containing the vendible articles or packages, mechanism for ejecting the articles from said magazine, a coin-carrier for conveying the deposited coin into position to operate said mechanism, and means whereby the deposited coin in said coin-carrier is automatically locked against operative movement when said magazine is empty, said coin-carrier being movable in a reverse 35 direction to permit withdrawal of the locked coin through the coin-entrance slot.

6. In a coin-controlled vending machine, a casing provided with a coin-entrance slot, a magazine for containing the vendible articles or packages, mechanism for ejecting the articles from said magazine, a coin-carrier for conveying the deposited coin into position to operate said mechanism, a yieldable 45 obstruction in the path of the coin on the carrier, and means whereby said obstruction is automatically locked against yielding when the magazine is empty, so that the coin in the coin-carrier is locked by said obstruction against further entrance into the 50 machine, said coin-carrier being movable in a reverse direction to permit withdrawal of the locked coin through said coin-entrance slot.

7. In a coin-controlled vending machine, a 60 movable coin-carrier to convey the deposited coin into operative position, a yieldable member in the path of movement of the coin, said member being adapted to cooperate with the coin for locking said coin-carrier against return movement after a predeter-

mined amount of forward movement, a magazine for containing the vendible articles, mechanism operable through the medium of the deposited coin for ejecting said articles, and means whereby said member is locked against operative movement by the coin when the magazine is empty.

8. In a coin-controlled vending machine, a shallow and substantially rectangular casing provided with a magazine for the vendible articles, an ejecting device mounted to operate in the space or chamber between said magazine and the front wall of said casing, a supplemental frame piece secured to the front wall of said casing and provided with a recess, a coin-carrier mounted to operate in said recess to convey the coin into engagement with said device, and means whereby the coin is automatically discharged from said recess into said space or chamber.

9. In a coin-controlled vending machine, a main casing provided with a magazine for the vendible articles, mechanism within said casing for ejecting the articles from said magazine, a supplemental frame-piece secured to the front wall of said casing and provided with a recess, a coin-carrier mounted to operate in said recess to convey the coin into engagement with said mechanism, and means whereby the coin is automatically discharged from said recess into said main casing.

10. In a coin-controlled machine having a coin entrance slot, a coin-actuated member held normally in a predetermined position, a movable coin-carrier for conveying the deposited coin into position to actuate said member, and means whereby the deposited coin is positively locked against operative movement in the machine when said member is out of normal position, said carrier being movable in the reverse direction to project said coin through said slot for removal.

11. In a coin-controlled vending machine, a shallow and substantially rectangular casing having means to provide a pair of shallow and closely adjacent chambers arranged in planes parallel with the plane of the casing, a pivoted lever mounted to operate in one of said chambers and having a part 110 extending into the other chamber, a hand-operable coin-carrier rotatably mounted in the other chamber to carry the deposited coin against said part of the lever and thereby actuate the same, and means whereby the 115 coin is automatically discharged from said second chamber into said first chamber after said lever has been actuated a predetermined amount.

12. In a coin-controlled vending machine, a shallow and substantially rectangular casing having means to provide a pair of shallow and closely adjacent chambers arranged in planes parallel with the plane of the casing, a pivoted lever mounted to operate in 125 130

one of said chambers and having a part extending into the other chamber, a hand-operable coin-carrier rotatably mounted in the other chamber to carry the deposited 5 coin against said part of the lever and thereby actuate the same, and means where the coin is automatically discharged from said second chamber into said first chamber after said lever has been actuated a predetermined 10 amount, said lever and said coin-carrier being pivotally supported on the front wall of said casing.

13. In a coin-controlled vending machine, a shallow and substantially rectangular casing having means to provide a pair of shallow and closely adjacent chambers arranged 15 in planes parallel with the plane of said cas-

ing, a magazine within said casing to the rear of said chambers, a pivoted lever mounted to operate in one of said chambers, said lever having two arms, an ejecting device connected with one of said arms to eject the goods from the lower end of said magazine, the other arm extending into the other chamber a coin-carrier rotatably mounted in the 20 other chamber and adapted to carry the deposited coin into engagement with the other arm of said lever, whereby said lever is rocked to actuate said ejecting device, and a hand-operable member for rotating said coin-carrier.

In witness whereof, I hereunto subscribe my name this 30 day of April, 1917.

ALBERT D. GROVER.
